[57] CLAIM

The ornamental design for a saucer, as shown and de-
scribed.

DESCRIPTION

FIG. 1 is a perspective view of a saucer showing my
new design;

FIG. 2 is a side elevational view thereof, the opposite
side and the adjacent end sides being substantially simi-
lar thereto;

FIG. 3 is a top plan view thereof shown on a reduced
scale from that used in FIGS. 1 and 2; and

FIG. 4 is a bottom plan view thereof shown to the same
scale as used in FIG. 3.

FIG. 1

FIG. 2

FIG. 3

FIG. 4
